UNITED STATES PATENT OFFICE.

JOHN E. MITCHELL, OF KEOKUK, IOWA.

WASHING-MACHINE.

SPECIFICATION forming part of Letters Patent No. 315,812, dated April 14, 1885.

Application filed March 22, 1884. (No model.)

To all whom it may concern:

Be it known that I, JOHN E. MITCHELL, of Keokuk, in the county of Lee and State of Iowa, have invented certain new and useful 5 Improvements in Washing-Machines; and I do hereby declare the following to be a full, clear, and exact description of the invention, such as will enable others skilled in the art to which it pertains to make and use the same.

10 My invention relates to washing-machines, and more particularly to certain improvements on the machine patented to me July 10, 1883, No. 281,111.

The object of the present invention is to provide a machine of simple and durable construction, and one that will avoid the inconveniences incident to the use of my former machine.

The invention consists in the novel means 20 for hinging the cross-bar of the machine to its standard, in a novel automatic securing device for said cross-bar; in an improved form of rubber shaft and crank; in means for securing and operating the lever of the machine, and in various other features of construction, as will be fully described herein-after, and pointed out in the claims.

In the drawings, Figure 1 is a plan view of 30 my improved machine. Fig. 2 is a side view of the same. Fig. 3 is a vertical section. Fig. 4 illustrates the false bottom of the tub and the face of the oscillating rubber; and Figs. 5, 6, and 7 are sectional detail views.

A represents parallel standards secured 35 to base-blocks *a* and connected by a cross-bar, *b*. This bar *b* is provided centrally with a socket, *C*, which receives a tapering pivot, *C'*, secured rigidly to the center of an oscillating frame, *C'*, upon which the tub *C* is removably secured.

D represents a removable or false bottom secured within the tub by means of a tongue, *d*, and staple *d'*, and a staple, *d''*, and cross-pin *d'''*.

E represents a cross-bar pivotally secured 45 to the upper end of the standard *A* by means of arms *e*, secured to the sides of the standard by a pin, *e'*, passing through the arms and standard. The opposite end of the cross-bar

50 *E* rests upon a bracket, *F*, projecting from a drip-pan, *H*, secured to the inner side of the upper end of the standard *B*. A ring, *G*, fits

upon the end of the cross-bar and is secured thereto by a loop-pin, *g*. This ring *G* is drawn inwardly to release the cross-bar from its engagement with the bracket *F*, and to secure the bar it is only necessary to drop the bar upon the bracket (holding the ring up against the under side of the bar) and allow the ring by its own weight to fall and embrace the bracket. The drip-pan *H* is made of metal, to insure durability, and is designed to carry the water from a wringer arranged above the tub back into the latter. The bar *E* is provided at its center with an opening to receive 65 a flanged sleeve, *I*. Within this sleeve is secured a bearing-sleeve, *J*, projecting from a crank-arm, *K*, and secured by a cross-pin, *j*. The sleeve-bearing *J* is of square or equivalent form in cross-section to receive the shaft 70 *L* of the rubber *M*. This shaft *L* corresponds in cross-section to the sleeve-bearing *J*, thus allowing the rubber to be raised and lowered freely. Both the false bottom *D* and the under surface of the rubber are each provided 75 with two series of slats, arranged at right angles to each other. The slats *d* of the false bottom are secured at right angles to the slats *d'*, and the slats *m* of the rubber are at right angles to the slats *m'*. This arrangement of 80 slats effects a thorough agitation of the water in the tub. The tub and rubber (as will be explained) oscillate in opposite directions, so that the slats of the false bottom will force the water in currents to the center, and at the 85 same time the rubber slats (moving in the opposite direction) will tend to force the water to the outer edges of the tub. The constant reversal of the movements of the rubber and tub effects a continual reversal of the currents 90 of water, thus insuring the maximum agitation, and lessening materially the time and labor required to cleanse the clothes.

P represents an arm or bracket secured to the standard *A* by means of a prong, *p*, entering the standard, and a bolt, *p'*, passing through the standard and bracket and held by a nut. The outer end of the bracket *P* is of journal form and receives a flanged sleeve, *Q*, which enters an opening in the lever *O* and 95 is held by a pin, *Q'*.

N is a rod connecting the lower end of the lever *O* with the oscillating frame *C'*, upon which the tub is secured.

R is a similar rod connecting the outer end of the crank-arm K with the lever O above the center of the latter.

O' represents a treadle projecting from the lower end of the lever to admit of the application of foot-power as an auxiliary to hand-power in operating the lever.

It will be apparent from the above description that when the lever is operated the tub and rubber will be oscillated in opposite directions. The arms e e enable the cross-bar E to be raised to remove the rubber from the tub without contact with the drip-pan H. The rubber, by means of the construction of the shaft 15 L and its adjacent parts, may be readily raised and lowered. The lever O is securely held upon the standard A, and an automatic securing device for the bar E is provided.

Having fully described my invention, what 20 I claim as new, and desire to secure by Letters Patent, is—

1. The combination, with the standards, of a hinged cross-bar and a supporting-bracket, which latter receives the free end of the cross-bar, and a ring arranged upon said cross-bar 25 to engage the bracket, substantially as set forth.

2. The combination, with the standards A and B, of a cross-bar hinged to the standard A by arms e e below the top edge of the tub, 30 a bracket projecting from the standard B, and a ring pivotally secured upon the cross-bar to engage said bracket, substantially as set forth.

In testimony whereof I have signed this 35 specification in the presence of two subscribing witnesses.

JOHN E. MITCHELL.
